UNITED STATES PATENT OFFICE

2,513,871

HEATER WITH DOOR MOUNTED BURNER

Albert H. Hoops, Savannah, Ga.

Application December 26, 1944, Serial No. 569,841

1 Claim. (Cl. 126—93)

1

The invention relates to heaters and has as an object the provision of a heater utilizing a "pot" burner having improved features.

It is a further object to provide a burner of this character mounted for ready accessibility.

It is a further object to provide a "pot" burner having improved means for delivery of fuel thereinto.

It is a further object to provide a "pot" burner having air admission openings which, due to their shape and location, improve the operation of the burner.

It is a further object to provide a heater applicable to the heating of domestic water or to a circulatory space heater.

Further objects will appear from the following description when read in connection with the accompanying drawings showing illustrative embodiments of the invention and, wherein:

Figure 1 is an elevation partly in section.

Figure 2 is an elevation showing the burner swung to accessible position.

Figure 3 is a detail vertical section on line 3—3 of Figure 1.

Figure 4 is a detail vertical section through one of the openings in the flame generating portion of the burner.

Figure 5 is a plan view shown partly in section of the device closed for operation and showing in dotted lines the burner swung to accessible position.

Figures 6 and 7 are views similar to Figure 5 showing other forms of the invention.

Figure 8 is a front view of a circulatory space heater shown partially in central vertical section and with parts broken away to show interior structure in section.

Figure 9 is a plan view partially in section of the structure of Figure 8.

As shown in Figures 1 and 2, the device is applied to a water heater comprising a closed casing 10 containing a water coil 11 in accordance with the usual practice. As there shown the pot burner of the invention is shown mounted upon a door 13 hinged at 14 to the casing 10. Struts 15, shown as four in number, are utilized to support the burner on the door in the form shown.

The "pot" burner is shown as comprising, in accordance with the usual practice, a combustion chamber 16 and a flame initiating chamber 17 divided by means of a cast iron annular ring 18 supported upon lugs 19. An additional cast iron ring is indicated at 20 lying upon the upper opening of the burner as is usual.

2

The burner is shown as made in two parts 21 and 22 formed respectively with marginal flanges 23, 24 which overlap and may be secured together as by use of screws 25. The pots 21, 22 are preferably formed of heavy sheet material, as for instance of 16 gauge steel. The chamber 16 is formed with a multiplicity of air openings 26 and the chamber 17 with air openings 27. The form of the openings 27 is an important feature 10 of the present invention. This form is clearly indicated in Figure 4 of the drawing which shows an opening essentially downwardly sloping. This form may be secured by the drilling of the holes and then by the deformation of the walls 15 of the holes in the form shown in Figure 4 which may be produced by an impact properly applied to the upper and lower margins of the openings or it may be produced by the insertion of a rigid instrument that fits the hole and using the said 20 instrument as a lever to deform the upper and lower portion of the opening at a single movement of the lever.

The result of this form of openings in combination with the forced draft to be described, 25 which produces a superatmospheric pressure in the space 28 between the pots 21, 22 is that the jets of air entering the chamber 16 are downwardly directed upon the oil lying therein, thereby very greatly improving combustion.

To provide the forced draft referred to there is shown a blower 29 also mounted on the door of the device in the form of Figures 1—5 inclusive with its nozzle projecting through the door to a position in alignment with and spaced 30 from the collar 30 surrounding an opening 31 in the pot 21. To adjust the supply of air in the space 28 in accordance with the speed of the fan and of the requirements of combustion there is shown a sleeve 32 loosely carried by the nozzle 33 of the blower, which sleeve may be slid away from the collar 30 so as to allow any desired percentage of the air from the blower to escape into the casing outside of the pot 21. The blast of air from the blower 29 would produce a cold 35 spot upon the pot 22, to avoid which a shield 34 is shown as applied to the wall of the pot 22 as clearly shown in Figures 3 and 5.

The device, when used as a domestic water heater, is ordinarily placed in a basement, the floor of which is likely to be dusty or otherwise unclean and to avoid the picking up of dust, lint, etc. from the floor to be drawn into the intake of the blower 29, a stack 35 is shown which extends to a height above the floor where the air 55 is likely to be more free of dust.

To admit fuel to the burner there is shown a fuel supply line 36 secured to the casing as at 37, in connection with a flexible fuel pipe 38 leading to a fitting 39 which may be rigid. The fitting 39 delivers to an X 40 from which extends a pipe 41 leading directly into the inner pot 22 and from the cross 40 also extend lines 42, 43 delivering respectively to pipes 44, 45 providing additional inlets for fuel into the pot 22. As shown the inlets are 3 in number spaced uniformly about the pot. If desired, 2 inlets or more than 3 may be utilized, the object being to deliver oil at spaced points to the inner pot so that oil may be uniformly distributed thereabout without having to flow to the various positions while exposed to the combustion. This provision avoids to a great extent deposits of carbon which would result from the form of fuel delivery now common. The flexible conduit 38 is provided to permit the portion 39 to move with the burner as the door 13 is opened and closed without interference with the flow of fuel and as a consequence the combustion in the burner may be adjusted if desired while the burner is swung into the open and is therefore available for inspection and adjustment.

In the form of the invention shown in Figure 6 (the fuel line, not shown, may be of the form already illustrated) the blower is shown as placed at one side of the device and is not mounted upon the door 13. To permit movement of the burner, a flexible air delivery pipe 46 is shown as provided when the burner is located as here shown. The fuel line in this form of the invention, not shown, may be of the form of Figures 1 to 5.

In the form of the invention of Figure 7 the blower 29 is located at a point removed from the hinge of the door and the collar 47 for coaction with the nozzle 33. The blower is shown in a position to swing to register therewith when the door is closed. The fuel delivery in the device of Figure 7 may be the same as that shown in Figure 5. It is of course obvious that the flexible conduit 38, Figure 5, could be inside the casing 10 after the manner of the flexible air intake 46 of Figure 6 but the preferred position is as shown in Figure 5 whereby the flexible pipe is not subjected to the heat of the burner.

The circulatory heater of Figure 8 embodies the burner supported upon the hinged door as in the forms already described but in this form of the invention the casing 47 in which the burner is mounted is shown in the form of a drum closed at the top and bottom and having, aside from the door opening, only the opening for the flue 48. The outer casing 49 is open at the bottom and may be open at the top also but is preferably provided with a grill work, not shown, at the upper end to prevent large objects from falling in upon the heated top of the drum 47. The air therefore of a room in which the device is

placed is free to circulate from below, around the heated drum 47, and out at the top thereof.

As indicated in Figure 8 the interior of the drum 47 above the burner is partially divided by a baffle 50 which deflects the air and products of combustion from the burner over against one side of the drum from which it rises to the top of the drum and then flows downwardly to the flue 48 thereby assisting in heat transfer. The drum 49 is as shown provided with a large door 51 hinged as at 52 which may be opened to secure accessibility to the smaller door 13' and to the blower 29 carried by the latter door. Opening of the large door enables the swinging open of the door 13' to bring the burner into the open in the manner already described in connection with the hot water heater.

Minor changes may be made in the physical embodiments of the invention within the scope of the appended claim without departing from the spirit of the invention.

I claim:

A heater comprising, in combination a heat exchange casing provided with a door; a pot burner mounted on said door for swinging outwardly and inwardly relative to the casing; said burner having an air admission opening surrounded by an outwardly directed collar; a blower mounted on said door independently of said burner, with a nozzle the periphery of which is substantially aligned with and spaced from the free edge of said collar; and adjustable means to vary the opening of said space between the collar and nozzle.

ALBERT H. HOOPS.
